OFF-SET TRIAL PROSTHESIS DEVICE FOR USE IN HIP PROSTHESIS SURGERY

William Minor Deyerle, 2222 Monument Ave.,
Richmond, Va. 23220

Filed May 1, 1973, Ser. No. 356,365

Term of patent 14 years

Int. Cl. D24—03

U.S. CL. D83—1 E

FIG. 1 is a front elevation view of an off-set trial prosthesis device for use in hip prosthesis surgery, showing my new design;

FIG. 2 is a side elevation view thereof, viewed from the left of FIG. 1;

FIG. 3 is a rear elevation view thereof;

FIG. 4 is a side elevation view thereof; viewed from the right of FIG. 1;

FIG. 5 is a top plan view thereof; and

FIG. 6 is a bottom view thereof.

I claim:

The ornamental design for an off-set trial prosthesis device for use in hip prosthesis surgery, as shown.
